UNITED STATES PATENT OFFICE.

GEORGE M. HUBBARD, OF NEW HAVEN, CONNECTICUT, ASSIGNOR TO
W. & E. T. FITCH, OF SAME PLACE.

DESIGN FOR A HARNESS-TERRIT.

SPECIFICATION forming part of Design No. 16,569, dated March 16, 1886.

Application filed November 23, 1885. Serial No. 183,790. Term of patent 7 years.

To all whom it may concern:

Be it known that I, GEORGE M. HUBBARD, of New Haven, in the county of New Haven and State of Connecticut, have invented a new 5 Design for Harness-Terrets; and I do hereby declare the following, when taken in connection with accompanying drawing and the letters of reference marked thereon, to be a full, clear, and exact description of the same, 10 and which said drawing constitutes part of this specification, and represents a face view of a terret.

This invention relates to a design for that 15 part of a harness-saddle through which the reins are guided, and what are commonly known as "terrets;" and the design consists in the configuration as hereinafter described, and as shown in the accompanying drawings.

From the base *a* the sides *b c* extend, curved

upwardly, and thence curved outward by a reverse curve, then obliquely upward and inward, connected across the top by a horizontal bar. 20

I claim—

The herein-described design for harness- 25 terrets, consisting of the base *a*, sides *b c*, extending from the base, curved upward, thence outwardly by reverse curve, and thence obliquely upward and inward, and connected horizontally at the top, as described and 30 shown.

GEORGE M. HUBBARD.
